UNITED STATES PATENT OFFICE.

EDWARD H. ROY, OF NASHVILLE, TENNESSEE.

HEAD HAND-MIRROR.

1,324,133.

Specification of Letters Patent. Patented Dec. 9, 1919.

Application filed May 7, 1919. Serial No. 295,427.

To all whom it may concern:

Be it known that I, EDWARD H. ROY, a citizen of the United States, residing at Nashville, in the county of Davidson and State of Tennessee, have invented certain new and useful Improvements in Head Hand-Mirrors, of which the following is a specification.

This invention relates to hand mirrors and has as its primary object to provide a hand mirror by the use of which one may obtain a view of those portions of his head which cannot be viewed by looking directly into a single mirror, and more particularly 15 the back and top of the head.

Another object of the invention is to provide a hand mirror which may be conveniently held so that the user may view any portion of the back or top of his head without being required to turn his head to an 20 inconvenient or uncomfortable position and without being required to shift his line of vision so as to cause discomfort to the eyes.

In the accompanying drawing:

25 Figure 1 is a view in side elevation of the mirror embodying the present invention, the view illustrating the manner in which the mirror is to be used;

Fig. 2 is a plan view of the mirror in use.

30 The device embodying the invention comprises a handle or hand grip 1 of any suitable construction and fixed to the upper end of this handle is the intermediate portion of a supporting member which is indicated in 35 general by the numeral 2. This supporting member comprises arms 3 which extend generally in opposite directions from the upper end of the handle 1 and the said member is preferably in the nature of a bar or rod 40 of metal bent to bowed form throughout the greater portion of its length as indicated by the numeral 4 and having its terminal portions bent to extend upward as indicated by the numeral 5, the member 2 except for its 45 said terminal portions 5, occupying, in use, substantially a horizontal plane as will be evident by reference to Fig. 1 of the drawings.

Upon the upper end of each terminal portion 5 there is supported in any desired manner a mirror, one of these mirrors being indicated by the numeral 6 and the other by the numeral 7. These mirrors 6 and 7 occupy vertical planes and it is preferable that 55 these planes be non-parallel, the arrangement being such that the planes occupied by

the two mirrors will be oblique to the length of the bar and will converge in the direction in which the portion 4 of the supporting bar 2 is bowed, or, in other words, in an outward direction when the device is held in position for use as in Figs. 1 and 2 of the drawing. The angle of inclination of the mirrors may be varied from that shown in the drawing and in fact, if desired, the mirrors 6 and 7 60 may be supported for rotative adjustment upon the respective terminal portions 5 of the supporting bar although it usually will suffice if the mirrors are fixed at predetermined angles considered to be the best for 65 the most convenient and effective use of the device.

The manner of using the device is clearly illustrated in the drawings and from the drawings it will be understood that the device is to be supported by grasping the handle 1 in either hand and supporting the device so that the portion 4 will bow outward from the neck of the user. The support 2 is of such length that the mirrors 6 75 and 7 will be so spaced that when the device is properly supported one mirror, as for example the mirror 6, when the device is held at the left side of the user, will be located a suitable distance in front of the user's face 80 and the other mirror 7 will be located a suitable distance rearwardly of the back of his head. Of course, when the device is held at the right side of the user the mirror 7 will be in front of the face and the mirror 90 6 back of the head. In any event the device as a whole may be moved in an arc about the head and caused to assume various positions so as to enable the user to view in that mirror which is in front, the reflection from the other mirror, of the back of his head. Also the device may be used so 95 that the user may conveniently view the top of his head by holding the device so that one of the mirrors will be located in front 100 of his face and the other in proper position above the head. By providing the bowed portion 4, the supporting bar 2 may stand relatively close to the neck of the user of the device and thus a wide range of adjustment 105 of the mirrors with regard to the face and back of the head of the user may be obtained and the usefulness of the device greatly enhanced. It will be understood, of course, 110 that the mirrors may be of any desired type and, of course, of any desired shape and size.

Having thus described the invention, what is claimed as new is:

In a duplicate mirror, a supporting bar having upturned ends, a handle depending rigidly from its center by which said member may be held horizontally above one shoulder of the user, the bar being bowed

outward between its ends, and mirrors carried by said ends and standing in planes oblique to the length of the bar and converging outward toward each other. 10

In testimony whereof I affix my signature.

EDWARD H. ROY. [L. s.]
